REPEATING MECHANISM FOR TELEGRAPH CIRCUITS.
APPLICATION FILED NOV. 3, 1908.

Patented Feb. 22, 1910.

950,047.

UNITED STATES PATENT OFFICE.

JAMES GRANT KERR, OF LONDON, ONTARIO, CANADA.

REPEATING MECHANISM FOR TELEGRAPH-CIRCUITS.

950,047.

Specification of Letters Patent. Patented Feb. 22, 1910.

Application filed November 3, 1908. Serial No. 460,979.

To all whom it may concern:

Be it known that I, JAMES GRANT KERR, residing at London, in the Province of Ontario, Dominion of Canada, have invented 5 certain new and useful Improvements in Repeating Mechanism for Telegraph-Circuits, of which the following is a specification.

My invention relates to certain new and 10 useful improvements in repeating mechanism for telegraph circuits, and it primarily has for its object to provide a self-adjusting sounder and repeater of a simple and effective construction which will quickly and 15 effectively serve its intended purposes.

Generically, the invention resides in providing an extra local magnet connected in series with the battery and regular local magnet of the sounder and arranged to operate on the opposite end of the sounder bar from that upon which the regular sounder 20 magnet operates (the pivot being between).

The invention also resides in the provision of circuit closing contacts operated by 25 the sounder, one in advance of the other one set of contacts controlling the extra magnet of another sounder while the other contacts control a main line repeating circuit.

Each relay and repeating station 30 embodies two main relays and their keys in the main line circuit, a local circuit from the relay to a respective sounder, the local circuit for one sounder including a pair of contacts on the opposite sounder and including its own main and extra sounder 35 magnets, the other sounder contacts being cross-connected in the main lines.

More specifically my invention resides in 40 those novel details or arrangement of operative parts and circuit, all of which will be first described in detail and then be specifically pointed out in the appended claims, reference being had to the accompanying drawing, in which the figure is a diagrammatic representation of my invention.

Referring now to the accompanying drawing 45 in which like numerals and letters of reference indicate like parts in the figure, 1 designates the "east" line and 2 the "west" line, while S³ designates the sounder that is actuated when impulses occur in the "east" line, and S⁴ the sounder for the "west" line:

50 The relay R⁵ has its magnet 5^a connected

in series with the "east" line 1 through a wire 5^b, while the relay R⁶ has its magnet 6^a connected in series with the "west" line 2 through a wire 6^b. The relay R⁵ in the "east" line controls the sounder S³ that repeats into the "west" line, while the relay R⁶ controls the sounder S⁴ that repeats into the "east" line. The relay R⁵ is grounded through a key K⁷ and main battery B⁹ while the relay R⁶ is also grounded through a key K⁸ and a main battery B¹⁰. Each relay R⁵ and R⁶ is provided with an armature 5^c—6^c respectively, that is spring held against a back stop 5^e—6^e respectively, while the forward movement of the armatures 5^c—6^c are 60 respectively limited by front stops 5^f—6^f, as shown in the drawing. The back stop of each relay R⁵—R⁶ is in my invention, utilized as a contact point in the respective local circuits. 75

The sounder bars 3^a—4^a of the respective sounders S³—S⁴ are each provided with an insulated contact segment 3^b—4^b to coöperate with a fixed contact 3^c—4^c respectively, while on the other end beyond the pivot x, 80 the bars 3^a—4^a are provided with a flexible or resilient contact 3^d—4^d respectively, to coöperate with the fixed contact 3^e—4^e to which the "west" and "east" wires 2 and 1 are respectively connected. 85

The contact 3^d is electrically connected by a wire 6^b to the magnet 6^a of the relay R⁶ while the contact 4^d is connected through a wire 5^b with the magnet 5^a of the relay R⁵. Each sounder S³—S⁴ also includes the regular operating magnet 3^m—4^m respectively and an auxiliary magnet 3ⁿ—4ⁿ of lesser convolutions and resistance than the principal magnets 3^m—4^m. The magnets 3^m—3ⁿ and 4^m—4ⁿ are respectively connected in series 90 with one another and with a respective local battery LB¹¹ and LB¹². One terminal of the local battery LB¹¹ is also connected through a wire 11^a to the armature 5^c of the relay R⁵ while the terminal of the local battery LB¹² is connected through wire 12^a of the armature 6^c of the relay R⁶. 100

The fixed back stop 5^e of the relay R⁵ is connected through a wire 13^b to the fixed stop 4^c of the opposite sounder S⁴, while the fixed stop 6^e of the relay R⁶ is also cross-connected by wire 14^b to the fixed stop 3^c of the sounder S³.

The connection 13 between the magnets 3^m—3ⁿ of the sounder S³ is connected by a 110

wire 13^a to the contact 4^b on the sounder bar 4^a of the sounder S⁴, while the connection 14 between the magnets 4^m—4ⁿ of the sounder S⁴ is connected through a wire 14^a with the 5 contact 3^b of the bar 3^a of the sounder S³. Thus it will be seen that when contacts 4^b—4^c, 5^e—5^c are closed, the magnets 3^m—3ⁿ of the sounder S³ will be thrown into parallel and since the extra magnet 3ⁿ is of less 10 convolutions and is of lesser resistance than the magnets 3^m when this action takes place the battery is short-circuited through the extra magnet and entirely away from the regular magnet as the current instead of 15 going through the regular magnet goes through the short-circuit via contacts 4^b—4^c—5^e—5^c, hence the regular magnet has lost its power and has none to be overcome—this is a case where the extra magnet does not over- 20 come the regular magnet. When, however, the action is reversed by the opening of the contacts the regular magnet then does have to overcome the magnetism in the extra magnet as the regular magnet can only get 25 current via the extra magnet. In other words, the extra magnet has current in greater or less degree flowing through it all the time.

By reason of the provision of the contacts 3^d—4^d the main line circuits are opened 30 after the local circuits of the different circuits are opened, and conversely such local circuits are closed after the closing of the main line circuits when the normal positions 35 of the sounder bars are resumed.

Assume the operator at the end of the "east" line run opens his key, breaking the "east" line circuit, (or if key K⁷ is opened) the relay magnet 5^a of the relay R⁵ will be 40 deenergized, thus releasing its armature 5^c to engage the back stop contact 5^e and close its local circuit from local battery LB¹¹, to armature 5^c, to contact 5^e, through wire 13^b, across contacts 4^c—4^b, through wire 13^a and 45 magnet 3ⁿ, back to battery LB¹¹, thus short-circuiting battery through magnet 3ⁿ and practically deenergizing magnet 3^m, (it being understood magnet 3^m is of greater resistance than magnet 3ⁿ having more convolutions of wire) thus overcoming the action 50 of the magnet 3^m and rocking bar 3^a until the local circuit of the relay R⁶ is opened at contacts 3^b—3^c and the "west" line circuit is opened at contacts 3^d—3^e. The opening 55 of the local circuit of the relay R⁶ occurs at contacts 3^b—3^c before the main line "west" is opened at contacts 3^d—3^e to prevent the sounder S⁴ from operating when the relay R⁶ in the "west" line circuit 60 "drops" its armature 6^c against the back stop contact 6^e.

Upon the closing of the "east" line circuit again by the operator, the relay R⁵ is again energized to attract its armature and 65 open its local circuit, thus relieving the short

circuit of local battery LB¹¹ through magnet 3ⁿ and allowing the local battery LB¹¹ to again send current through the magnets 3^m—3ⁿ in series and since the magnet 3^m has more convolutions than magnet 3ⁿ, it will 70 overcome the action of the magnet 3ⁿ and attract the bar 3^a to rock it in an opposite direction to first close the circuit in the main line "west" (to energize relay R⁶ to first open contacts 6^c—6^e) and then closing the 75 local circuit of the relay R⁶ at contacts 3^b—3^c again. When the "west" line is opened and closed a corresponding operation of the sounder S⁴ and relay R⁶ takes place.

Suitable switches (not shown) may be 80 provided to cut out the breaking points when desirable, to operate the two lines independently, as will be well understood by those skilled in the art to which the invention appertains.

It will also be noted that by providing the main and auxiliary sounder magnets in series with one another they become self-regulated, that is to say, the sounder bar is balanced when not under the influence of either 90 magnet any variation in the battery strength will not affect the operation of the sounder, since should the battery current become weaker and weaker the current in the main and auxiliary magnets will each be reduced 95 without affecting their relative magnetic value.

From the foregoing description taken in connection with the accompanying drawing, it is thought the complete construction, operation and advantages of my invention will be readily understood by those skilled in the art to which the invention appertains.

What I claim is:—

1. A sounder and repeating mechanism 105 comprising in combination with the "east" and "west" lines, of a sounder for each line, each sounder including a pivoted sounder bar, and a pair of magnets therefor, each sounder having make and break contacts in series with its respective line, a relay 110 for each "east" and "west" line having one terminal of its magnet connected to the line and the other terminal grounded, a local circuit for each relay through its corresponding sounder magnets, said magnets of each sounder operating one of each set on the sounder bar on one side of its pivot and the other of the set operating on the sounder bar at the other side of its pivot, means controlled by one sounder for making and breaking the local circuit of the other sounder at times, each of said local circuits including a source of electrical energy common to both sounder magnets.

2. In a telegraph sounder and repeater, a pair of main line circuits, a relay and a source of electric energy connected in each of said main line circuits, a local circuit including a source of electric energy for each 130

- of said local relays, a sounder for each circuit, said sounders each having a pair of magnets connecting in the respective local circuit, and a source of energy common to 5 both of said magnets, and means carried by one sounder for controlling the local circuit of the opposite sounder and relay, and means controlled by one sounder for repeating into the opposite line.
- 10 3. In a sounder and repeater, a pair of main line circuits, each including a source of electric energy, an operating key and a relay, the operating magnet of which being connected in said main line circuit, a local 15 circuit including a source of electric energy for each of said relays, a sounder having a main and an auxiliary operating magnet connected in series with each of said local circuit source of electric energy to hold the 20 sounder bar normally in one position, and means controlled by one sounder for disturbing the magnetic relation of the main and auxiliary magnets of the other sounder at times.
- 25 4. In a sounder and repeater, a pair of main line circuits, each including a source of electric energy, an operating key and a relay, the operating magnet of each being connected in said main line circuit, a local 30 circuit including a source of electric energy for each of said relays, a sounder having a main and an auxiliary operating magnet connected in series with its respective local circuit source of electric energy to hold the 35 sounder bar normally in one position, means controlled by one sounder for disturbing the magnetic relation of the main and auxiliary magnets of the other sounder at times, and means controlled by each sounder 40 for making and breaking one of said main line circuits.
5. In a sounder and repeater, a pair of main line circuits, each including a source of electric energy, an operating key and a 45 relay, the operating magnet of which being connected in said main line circuit, a local circuit including a source of electric energy for each of said relays, a sounder having a main and an auxiliary operating magnet 50 connected in series with its respective local circuit source of electric energy to hold the sounder bar normally in one position, means controlled by one sounder for disturbing the magnetic relation of the main and auxiliary 55 magnets of the other sounder at times, and means controlled by each sounder for making and breaking one of said main line circuits after the local circuit controlled by said sounder has been disturbed thereby.
- 60 6. In a sounder and repeating mechanism, in combination with the armature of the local sounder and the main electro-magnet thereof, of a supplemental electro-magnet, a local battery common to both the main 65 and supplemental electro-magnets and a
- breaking point included in a circuit, which breaking point opens before the circuit of the main line is broken.
7. In a repeating mechanism for telegraphs, the combination of a main line relay armature with a closing contact point on its back stop, a local sounder, a supplemental local magnet on said local sounder for the purpose of actuating the sounder bar thereby opening its local and main line 70 breaking points, said sounder having local and main line breaking points said supplemental local magnet being operatively opposed to the main sounder magnet.
8. In a repeating mechanism, a pair of 80 main line circuits, a relay for each of said circuits having its magnet connected in the respective circuit, a sounder for each circuit having a main and an auxiliary magnet operating normally in opposition to one another on the sounder bar, one of said magnets being of sufficient strength to normally overcome the other one, a local circuit including a source of electric energy connected with said relay and said magnets, all being 85 arranged whereby when the local circuit is closed by the relay the relative action of the main and auxiliary magnets will be reversed, substantially as shown and described.
9. In a repeating mechanism, a pair of 90 main line circuits, a relay for each of said circuits having its magnet connected in the respective circuit, a sounder for each circuit having a main and an auxiliary magnet, operating normally in opposition to one 95 another on the sounder bar, one of said magnets being of sufficient strength to normally overcome the other one, a local circuit including a source of electric energy connected with said relay and said magnets, all 100 being arranged whereby when the local circuit is closed by the relay the relative action of the main and auxiliary magnets will be reversed, and means for preventing such 105 reversal at times.
- 110 10. In a repeating mechanism, a pair of main line circuits, a relay for each of said circuits having its magnet connected in the respective circuit, a sounder for each circuit having a main and an auxiliary magnet 115 operating normally in opposition to one another on the sounder bar, one of said magnets being of sufficient strength to normally overcome the other one, a local circuit including a source of electric energy connected 120 with said relay and said magnets, all being arranged whereby when the local circuit is closed by the relay the relative action of the main and auxiliary magnets will be reversed, and means controlled by one sounder for 125 opening the local circuit of the other sounder before it is closed by its relay at times.
11. In a repeating mechanism for telegraphs, a pair of main line circuits, a relay for each of said circuits having its magnet 130

connected in the respective circuit, a sounder for each of said circuits having a main and an auxiliary magnet operating normally in opposition to one another on the sounder bar, 5 one of said magnets being of sufficient strength to normally overcome the other one, a local circuit including a source of electric energy connected with said relay and said magnets, all being arranged whereby when 10 the local circuit is closed by the relay the

relative action of the main and auxiliary magnets will be reversed, and means controlled by one sounder for first opening the local circuit of the other sounder and then opening the opposite main line circuit to de- 15 energize the relay of such opposite circuit.
